BURNER CONTROL SYSTEM

Willis H. Gille, St. Paul, Minn., assignor to Minneapolis-Honeywell Regulator Company, Minneapolis, Minn., a corporation of Delaware

Application September 30, 1938, Serial No. 232,607

14 Claims. (Cl. 158—28)

The present invention relates to a burner control system and more particularly to one having improved means for checking the presence of a pilot flame before fuel is supplied to the main burner.

It is the conventional practice with burner control systems to provide some means for insuring that fuel is not supplied to the main burner until such time as the pilot burner is properly ignited. In relatively small burner installations the speed of response of the pilot flame responsive means is not particularly important so that it is possible to use various temperature responsive devices for performing this function. In large industrial installations, however, it is highly imperative that particularly in the event of flame extinguishment, the supply of fuel to the main burner be interrupted immediately. Many of these large burners consume an enormous quantity of fuel and within a very short period of time sufficient unignited fuel may be supplied to the fuel chamber to cause a serious explosion. It has, accordingly, been proposed to place an electrode in the pilot burner flame, the burner flame forming a portion of a conductive path. The potential across the burner flame is then used to control the fuel flow to the main burner. In one preferred form, the potential across the pilot burner flame is used to control the grid voltage of a space discharge tube, the output of which controls a relay which, in turn, controls some fuel flow controlling device such as a gas valve or an oil burner motor.

The difficulty that has arisen with devices of the type last mentioned is that it is often necessary to have a lead of appreciable length between the casing housing the space discharge tube relays and other associated control devices and the electrode positioned in the pilot burner flame. In order to raise the grid voltage upon the presence of a flame, it is necessary that the pilot burner be connected to a voltage source so that a relatively high potential exists between the pilot burner and the electrode. In order to have the apparatus safe, it is necessary to ground the pilot burner and to shield the lead between the electrode and the control apparatus, this shield being also grounded. The presence of this long grounded lead between the control apparatus and the electrode creates a possible hazard of a false indication of a flame by reason of leakage or capacity effect between the lead and the shield surrounding the same. As will be noted from the above description, the insulation between the lead

or conductor and the surrounding shield is, in effect, connected in parallel with the gap between the pilot flame electrode and the pilot burner, both being subjected to quite a high voltage. Where an alternating voltage is employed as is often desirable, the capacity effect in a long lead may be very appreciable and in view of this high voltage it is very possible for the current flow which is normally indicative of the presence of a pilot burner flame to actually take place between the conductor and the surrounding shield. This danger has previously made it desirable to employ direct current voltages with the resultant increase in expense in order to get satisfactory operation. Even then the danger of leakage was always present to a certain extent.

A further difficulty with these prior devices is the possibility of a false indication of flame being given as the result of a grounded electrode or similar condition causing a very low resistance between the electrode and ground. In my prior application, Serial No. 61,398, filed January 2, 1936, I have disclosed such a system in which a check is provided against a grounded electrode before the pilot burner is placed in operation. It often happens, however, that such a grounded condition may not arise until after the main burner has been supplied with fuel. As many burners will not stay properly ignited without the presence of an ignited pilot burner, it is desirable that there be some means of terminating burner operation if the resistance between the electrode and ground becomes abnormally low at any time.

While a system has been devised overcoming certain of the above named disadvantages, this system provides the disadvantage that its operation demands the decrease of the output current of a space discharge triode unit upon the presence of flame and the increase of such output current in the event of there being no flame. This has the obvious disadvantage that any failure of this triode will give a false indication of flame.

An object of the present invention is to provide a burner control system having a flame detecting arrangement of the type referred to above in which the effect of capacity and leakage is minimized and in which upon the existence of excessive capacitive effect or leakage, the grid of the space discharge tube having the flame as a portion of its grid circuit is subjected to such a large negative voltage that the discharge of the tube and consequently the flow of fuel to the burner is prevented.

A further object of the present invention is to

provide an intermediate shield between the outer grounded shield and the conductor which is connected to the grid in such a manner that normal capacitance and leakage do not affect the operation of the system and that in the event of excessive capacitive effect or leakage the grid is subjected to a negative voltage such that the flow of fuel to the burner is prevented.

A further object of the present invention is to provide a burner control system having such a flame detecting arrangement in which the presence of an abnormally low resistance between the flame electrode and ground will always prevent further burner operation by increasing the negative bias on the grid.

A further object of the invention is to provide such a burner control system in which upon either the flame being extinguished or the resistance between the flame electrode and ground being reduced so as to make liable a false indication of flame, the negative bias on the grid circuit is increased so as to prevent burner operation.

Further objects of the present invention will be apparent from a consideration of the accompanying specification, claims and drawings of which:

Figure 1 is a schematic view of one form of the improved burner control system:

Figure 2 is a diagrammatic view of a portion of the system of Figure 1;

Figure 3 is a schematic view of a modified form of the improved burner control system; and of which

Figure 4 is a vector diagram showing the relation between the various voltages across different points of the circuit of Figure 3.

Referring to the drawings for a more complete understanding of the present invention, the system is shown as employed in connection with an oil burner. It is to be understood, however, that the invention is not so limited and that any other fuel burner arrangement such as a gas burner and an associated gas valve may also be employed. The oil burner is indicated in the drawing by the reference numeral 10. The burner is of conventional form and comprises a nozzle 11 and a motor 12 which serves to drive a blower forcing an atomized mixture of fuel and air through the nozzle 11. Located adjacent to the burner 10 is a pilot burner 14 supplied by a pipe 15 with a suitable fuel such as gas. It is to be understood that the fuel issuing from nozzle 11 is ignited by the burner 14 if the same is properly lighted. It is, accordingly, imperative that it be assured that the burner 14 is lighted before the oil burner is placed in operation. While the pilot burner is shown as of the constantly burning type, it is to be understood that the invention is equally applicable to one in which the pilot burner is lighted by separate ignition means each time the oil burner is placed into operation.

A relay is employed to control the operation of the oil burner. This relay is indicated by the reference numeral 20 and comprises a relay coil 21 and a pair of switch blades 22 and 23. Switch blade 22 is biased into engagement with a fixed contact 24. The switch blade 23 is biased out of engagement with a fixed contact 25. Upon energization of the relay coil 21, switch blade 22 is moved out of engagement with contact 24 and switch blade 23 into engagement with contact 25. A condenser 27 is connected in parallel with relay coil 21 to con-

ductors 28 and 29. The function of condenser 27 is to filter out the pulsations in the energizing current for the relay and to decrease any chattering action of the relay. A space discharge device 30 controls the energization of relay 20. The space discharge device 30 may take the form of an ordinary thermionic vacuum tube although the invention is not so limited. In any event, the device comprises a cathode 31, a grid 32, and an anode 33.

A combination step-up step-down transformer is employed for supplying the necessary power for operation of the vacuum tube and the control system associated therewith. This transformer is indicated by the reference numeral 36. The transformer comprises a line voltage primary 37 connected to line wires 38 and 39 leading to a suitable source of power (not shown). The transformer also comprises a center tapped secondary 41 for energizing the heater element of the cathode 31. In the embodiment shown, the cathode 31 is of the filament type although it is to be understood that an indirectly heated cathode may be employed. The transformer 36 also comprises a secondary 42 which is for the purpose of supplying the necessary voltage for the anode circuit of the vacuum tube and the various voltages applied to the grid circuit.

A thermostat 45 is used for controlling the energization of the filament and consequently the operation of the vacuum tube. The thermostat 45 comprises a bimetallic element 46 to which is secured a contact arm 47 adapted to be moved in and out of engagement with a fixed contact 48. A magnet 49 is associated with the contact arm 47 and serves to impart a snap action thereto. This snap action movement which the magnet causes both reduces sparking in the contacts to a minimum and also insures the necessity of a temperature differential in the operation of the thermostat to prevent an excessive number of operations or a chattering action. The thermostat 45 may be located at any desired controlling point, such as a room or other space being heated.

Also controlling the energization of the filament 31 is a thermal safety switch generally indicated by the reference numeral 50. This switch may take any suitable form, one preferred form being that shown in the patent to Frederick S. Denison, No. 1,958,081, issued May 8, 1934. As shown in the drawing for purposes of illustration, the switch comprises a pair of switch blades 51 and 52, the lower end of switch blade 52 being pivotally mounted as at 53. Located underneath the right-hand end of switch blade 52 is a bimetallic element 54. The bimetallic element 54 is shown in its cold position, in which position it is effective to maintain switch blade 52 in engagement with switch blade 51. Located adjacent to bimetallic element 54 is a heater element 55. This heater element when energized serves to warp bimetal element 54 to the right. If this heating action is continued sufficiently long, the bimetal element 54 will be warped sufficiently to the right to permit switch blade 52 to drop away from switch blade 51. After this has happened, it is impossible for the switch blades 51 and 52 to move together without being reclosed manually.

The grid 32 is connected through conductors 60 and 61, resistance 62, and conductor 63 to the uppermost terminal of secondary 42. Inasmuch as the opposite end of the secondary 42 is the one which is connected to the anode 33,

the upper end of the secondary 42 is the point of lowest potential when the direction of the potential is such that the tube 30 passes current. The mid point of filament secondary 41 is connected by a conductor 65 to a tap 67 of the secondary 42. It will be noted that the tap 67 is at an intermediate point of the secondary 42. Thus considering the half cycle during which the tube 30 is passing current, which half cycle is the only one of interest so far as the grid circuit is concerned, the connections between the grid 32 and the secondary 42 through resistor 62 tend to cause the grid to assume a potential below that of the cathode 31. If it were not for the potential drop through the resistor 62, this difference in potential would be the potential difference between tap 67 and the upper end of the secondary 42. However, due to the potential drop through resistor 62 this potential difference between the grid and the cathode is considerably reduced but is still sufficiently great that when the voltage on grid 32 is determined solely by this connection, the tube is biased to such a point that no anode current flows therethrough.

It will be noted that the lowermost point of the secondary 42 is connected to ground at 68. This point is the point of highest potential during the half cycle that the tube is passing current. A second circuit exists between the grid 32 and the secondary 42, when the pilot burner is lighted, as follows: grid 32 through conductors 60 and 70, electrode 11, pilot burner flame 12, pilot burner 14, ground connection 13, through the ground connection 68 and conductor 74 to the lowermost point of secondary 42. As soon as this connection is established, the potential of the grid 32 is raised sufficiently as to cause tube 30 to pass anode current.

Surrounding the conductor 70 is a shield 75. While this shield is shown as connected over only a portion of the length of conductor 70, it is to be understood that in actual practice the shield 75 will extend all the way from the electrode to the point where the conductor 70 is entirely enclosed in a housing for the control apparatus. In order to insure that the shield 75 will at no time be at a dangerous potential with respect to ground, the shield is connected to ground as at 76. Interposed between the shield 75 and conductor 70 is an intermediate shield 78. The conductor 70 and shield 78 are separated from each other by an insulating layer 82 of extremely high dielectric strength. A similar layer 83 insulates the shield 78 from the outer shield 75. Shield 78 is connected through a conductor 79 to a tap 80 which during the conductive half cycle is at a lower potential than the tap 67 to which the cathode 31 is connected. The purpose of this intermediate shield and connection 79 will be discussed in more detail later.

Operation of species of Figures 1 and 2

The various elements of the system are shown in the position which they occupy when the temperature to which thermostat 45 is responsive is at or above the desired value. Let it be assumed that the temperature falls causing bimetallic element 46 to move contact arm 47 into engagement with contact 48. When this takes place, an energizing circuit is established to filament 31 as follows: from the upper terminal of secondary 41, through conductor 85, switch blades 52 and 51, conductor 86, contact 48, switch blade 47, bimetallic element 46, conductors 87 and 88, filament 31, and conductors 89 and 90 to the lower

terminal of secondary 41. The establishment of this circuit will start the heating of the filament 31. At the same time as the circuit is established to the filament 31, the following circuit is established to the heating element 55 of the 5 thermal safety switch 50: from the upper terminal of secondary 41 through conductor 85, switch blades 52 and 51, conductor 86, contact 48, contact blade 47, bimetal element 46, conductors 87 and 91, heating element 55, conductor 10 92, switch blade 22, contact 24 and conductors 94 and 90 to the lower terminal of secondary 41.

As soon as the filament 31 becomes sufficiently heated, current will flow through the following anode circuit providing that the grid potential is 15 sufficiently high: from the lowermost point of secondary 42 through conductors 74, 96 and 29, relay coil 21, conductors 28 and 97, anode 33, cathode 31, secondary 41, and conductors 65 to the tap 67 of secondary 42. Unless the pilot burner 20 is ignited, the grid will not have a potential sufficiently high to permit flow of current through this circuit. So long as there is no flame 72, the grid 32 is connected only to the upper end 25 of the secondary 42, which during the conductive half cycle is at the lowest potential. If there is a flame 72, however, the grid is not only connected to the upper end of the secondary 42 but is also connected to the lower end or the point of highest potential, as previously explained. 30

The energization of relay coil 21 results in switch blade 23 being moved into engagement with contact 25 with the result that the following circuit is established: from line wire 39 through conductor 99, switch blade 23, contact 25, conductor 100, burner motor 12, and conductor 101 to the other line wire 38. The establishment of this circuit results in the burner motor forcing a mixture of fuel and air through the nozzle 11, which mixture is ignited by the pilot burner 14. 40 In the case of a gas burning system, the circuit just traced would be to the gas valve so that the establishment thereof causes the valve to open, admitting gas to the burner.

Energization of relay 21 also results in switch blade 22 being moved out of engagement with contact 24 with the result that the previously traced circuit through heating element 55 is interrupted. The result of this is that the warping of bimetallic element 54 is terminated. If the energization of relay 21 occurs sufficiently quickly, switches 51 and 52 will accordingly never be separated. If, however, the pilot burner is extinguished at the time that the thermostat calls for heat or if for some reason the control apparatus is faulty, the heating of the bimetal will continue sufficiently long to allow switch blade 52 to separate from switch blade 51, completely deenergizing the filament circuit and consequently preventing the operation of the apparatus. 60

Inasmuch as the flame 72 has an extremely high resistance, it is necessary that the voltage between grid 32 and the burner 14 be relatively high in order that the establishment of the flame will result in an appreciable change in the potential of grid 32. In the prior art systems, the conductor extending between the grid 32 and the electrode 11 has been enclosed in a grounded shield corresponding to shield 75. It was necessary that this shield be grounded in order to 65 eliminate any danger of a person accidentally engaging the conductor receiving an electrical shock. The presence of this grounded shield, however, resulted in a path between the conductor 70 and ground parallel with the path to the 70 75

flame. It can be readily seen that particularly where an alternating current voltage was employed and there was appreciable capacity effect, the total impedance between conductor 70 and the shield 75 might be very little higher, if any, than the impedance of the flame 72. Even disregarding the capacity effect, any very slight tendency of leakage through the insulation between the conductor and the shield might result in a false indication of the flame. Such a false indication would, of course, be highly undesirable since the user would be relying upon the control apparatus for insuring that the burner was not turned on if there was no pilot flame.

15 The presence of the intermediate shield 78 in the device of the present invention not only lessens the tendency for capacity or a slight amount of leakage to effect the operation of the system but also insures that if such leakage or capacity effect become excessive the system will prevent fuel being supplied to the burner, or in other words, will "fail safe." The function of this intermediate shield can perhaps best be understood by reference to the schematic diagram of Figure 2. In this diagram, a number of elements of the system have been left out and the rest of the elements have been rearranged to more clearly indicate the relative potentials which the various elements are subjected to. In order, moreover, to more clearly understand the relative potentials of the various elements, the various potentials are indicated on the drawing at the values they may assume during the conductive half cycle. Thus let it be assumed that the cathode is at zero potential and the lower end of the secondary 42 is at plus 250 volts and the upper end at minus 150 volts. By reason of the potential drop through resistor 62, the grid 32, in the absence of flame 72, is at a potential close to that of tap 80, or, in other words, sufficiently negative with respect to the cathode that no anode current passes through the tube 30. Under these conditions, if there were no intermediate shield 78, the potential difference between the conductor 70 and the outer shield 75 would be over 250 volts. This relatively large potential difference would be sufficient to make the effects of any slight leakage or capacitance very evident and might lead to a false indication of the presence of flame 72. By reason, however, of the intermediate shield 78 connected to the winding 42 at tap 80 there is practically no potential difference between the conductor 70 and the shield 78. Thus even though there is a slight capacity effect and even though there is a slight amount of leakage, the potential difference between conductor 70 and the intermediate shield 78 is so slight that the leakage and capacitance will have practically no effect on the potential of the grid. While the grounded shield 75 still exists, the shields 78 and 75 are connected directly across the transformer secondary 42. Inasmuch as the transformer secondary 42 is capable of delivering a substantial amount of power, any slight conductance that may take place between shields 78 and 75 will not change the potential difference between these two shields. In other words, the shield 78 will continue to remain at the potential of tap 80. Even after the 70 grid 32 is connected through the flame 72 with the lower or high potential end of secondary 42, the voltage between conductor 70 and the intermediate shield 78 will still be relatively small. It must be borne in mind that all that it is necessary to do is to raise the grid potential slightly

by an amount less than the voltage between taps 80 and 67.

If for some reason or other, there should be an excessively low impedance between conductor 70 and the intermediate shield 78, the most serious condition that could happen would be that the grid 32 would assume a potential substantially equal to that at tap 80. This potential, as previously indicated, is such that the grid, if subjected to this potential, will prevent any flow of current through the tube. In other words, the tap 80 is at the "cut-off" potential.

With the species just described, it is thus possible to employ alternating current exclusively for the operation of the system and avoid the disadvantages of previous systems of this type. It will further be seen that the defects of the prior systems have been overcome in an extremely simple manner.

Species of Figures 3 and 4

20

While the system of Figures 1 and 2 has a distinct advantage over certain prior systems, this system does have the disadvantage, however, that it is not able to differentiate between a low resistance condition caused by a flame and that caused by a short circuit between the electrode and burner. As pointed out previously, it is desirable that the apparatus shut down in the event of a short circuit or partial short circuit condition between the burner electrode and the burner. If such shut-down does not occur, a false indication of flame will be given and the apparatus will fail to perform the function for which it was intended. The system of Figures 3 and 4 avoids this defect while retaining the advantages of the system of Figures 1 and 2.

25

35

Referring to Figures 3 and 4, a relay is generally designated by the reference numeral 110. This relay corresponds to the relay 20 of Figures 1 and 2. The relay comprises a relay coil 111 with which are associated switch blades 112 and 113. Switch blade 112 is biased into engagement with a fixed contact 114 and is adapted to be moved out of engagement therewith upon the energization of relay coil 111. Switch blade 113 is biased out of engagement with a fixed contact 115 and is adapted to be moved into engagement therewith upon energization of relay coil 111. The switch blade 113 and contact 115 connect to conductors 117 and 118, respectively, leading to a burner, valve, or other heater controlling device. A condenser 120 is connected in parallel with relay coil 111 to filter out the pulsations in the current supplied thereto and thus eliminate chattering of the relay.

45

50

55

The energization of relay coil 110 is controlled by a thermionic electronic tube designated by the reference numeral 123. This tube is preferably a vacuum type although other suitable tubes such as gas filled electronic tubes may be employed. The tube 123 comprises a cathode 124, a heater 125 therefor, a grid 126, and a plate 127. The construction being entirely conventional, no further explanation is needed.

60

65

A combination step-up step-down transformer 130 supplies power for operation of the system. The transformer comprises a primary winding 131 connected to line wires 132 and 133 leading to a suitable source of power. The transformer also comprises two secondary windings 135 and 136. The secondary winding 136 is employed for energization of the cathode heater 125. The secondary 135 is employed for supplying the power

70

75

80

for the control and output circuits of vacuum tube 123.

The operation of the system is controlled by a room thermostat 137 which is of conventional type and comprises a bimetallic element 138 to which is secured a contact arm 139. The contact arm 139 is adapted to be moved into engagement with a fixed contact 140 upon a temperature fall. A magnet 141 is associated with the 10 contact blade 139 and serves to impart a snap action thereto.

The thermostat 137 controls the operation of the system, as in the species of Figure 1, by controlling the energization of the cathode heater. Also controlling the energization of this 15 heater is a thermal safety switch 143 which is equivalent to the switch 50 of Figure 1. This switch comprises a rigid switch blade 144 and a pivoted switch blade 145, the pivoted switch 20 blade being held in the position shown in the drawing by a bimetallic element 146 which is heated by a heater 147. The operation being the same as switch 50 of Figure 1, no further explanation is deemed necessary.

25 The pilot burner is designated in Figure 3 by the reference numeral 150. This pilot burner is connected to ground by ground connection 151. An electrode 152 is adapted to project into the burner flame, this electrode being connected 30 to the grid 126 by a conductor 153. Surrounding the conductor 153 is a double shield consisting of an inner shield 154 and an outer shield 155. It is to be understood that this shield corresponds 35 in structure to the shield of Figure 1 and that the two shield members are insulated from each other and from the conductor 153 by a suitable dielectric.

For convenience in the subsequent description, the various taps of the transformer secondary 40 135 are designated by the reference numerals 160, 161, 162, 163 and 164. A conductor 168 extends from the tap 161 to a resistor 167. A conductor 168 extends from the tap 164 to a condenser 169. A conductor 170 is connected at one end to the 45 resistor 167 and at its other end to a conductor 171 extending from condenser 169. The junction of conductors 170 and 171 is designated by the reference numeral 172. The tap 163 is half way between the taps 161 and 164. The tap 163 is 50 connected by means of a conductor 174 to the center tap 175 of an autotransformer winding 176. The other end of the right half or primary half of the autotransformer is connected to junction 172. The opposite end of the winding 176 55 of the autotransformer is connected to ground by a ground connection 177. As will be more apparent from the subsequent description of the operation, the portion of secondary winding 135 between taps 161 and 164, the resistor 167, and 60 condenser 169 constitute a phase shifting bridge between the output terminals 163 and 172 of which the primary portion of the autotransformer winding 176 is connected. The impedance of resistor 167 is preferably the same as that of condenser 169 so that there is impressed across 65 the primary portion of the winding of secondary 176 a voltage which is 90 degrees displaced in phase from the voltage of the winding 135.

Connected to the terminal 172 of the autotransformer winding 176 through conductors 180 and 181 is a condenser 182, which condenser is in turn connected through conductors 183 and 184 with the flame electrode 152, the junction of conductors 183 and 184 being indicated by the 75 reference numeral 185. The flame electrode 152

is in turn connected to the burner flame, burner 150, ground connections 151 and 177 with the other terminal of the autotransformer winding 176. The autotransformer 176, the condenser 182, and the flame gap constitute a second phase 5 shifting bridge. The voltage applied to the second phase shifting bridge has the same phase relation to the supply voltage as the output of the first phase shifting bridge. In fact, this voltage applied to the second phase shifting 10 bridge is the output voltage of the autotransformer 176, the primary portion of which has impressed across it the output voltage of the first phase shifting bridge.

It will be noted that the grid 126 is connected 15 at junction 184 to conductor 153 which is one of the conductors joining condenser 182 to electrode 152. The junction between condensers 182 and flame electrode 152 constitutes one of the output terminals of the second phase shifting bridge. 20 The other output terminal of the second phase shifting bridge is the center tap 175 of autotransformer winding 176. The cathode 124 is connected to this tap 175 through conductor 185, a portion of the transformer winding 135 between 25 taps 162 and 163, and conductor 174. It will thus be noted that the grid circuit of tube 123 includes in series the output of the second phase shifting bridge and the section of the transformer secondary between taps 162 and 163. As will be pointed 30 out later, the anode 121 is connected to the tap 160 so that during the half cycle of the system in which the vacuum tube is passing current, tap 160 is the point of highest potential of secondary 35 135. Consequently, during this half cycle the tap 162 is at a higher potential than tap 163 so that the inclusion of this portion of the transformer secondary in the connection between the cathode and one terminal of the second phase shifting 40 bridge results in the grid being biased negatively in the event of the phase shifting bridge having a zero output or an output which is 90 degrees displaced in phase to the voltage of secondary 135. The value of the biasing voltage between taps 162 and 163 is so chosen that it is effective to bias the 45 grid so far negatively that insufficient current flows through relay coil 111 to operate the same.

Operation of species of Figures 3 and 4

It will be assumed that the temperature in the 50 space in which thermostat 137 is located falls sufficiently so as to cause switch arm 139 to engage contact 140. When this takes place, a circuit will be established to filament winding 125 as follows: from the lower terminal of secondary 136 through 55 conductor 187, bimetal 138, contact arm 139, contact 140, conductors 188 and 189, switch blades 145 and 144, conductor 190, cathode heater 125, and conductors 191 and 192 to the other terminal of secondary 136. This will result in the cathode 60 heater 125 warming up to heat the cathode 124 so that the tube becomes conductive providing the other conditions necessary to the conductance of the tube are established.

It will be noted that this filament circuit includes switch blades 144 and 145 of the thermal safety switch. At the same time that the circuit to filament heater 125 is established, a circuit is also established to the safety switch heater 147 as follows: from the lower terminal of secondary 70 136 through conductor 187, bimetal 138, contact arm 139, contact 140, conductors 188 and 193, heater 147, conductor 194, contact 114, switch blade 112, and conductors 195 and 192 to the upper terminal of secondary 136. The result is

that the bimetallic element is heated by heating element 147 so that unless heater 147 is deenergized within a predetermined period of time, switch blades 144 and 145 will be separated to deenergize the system.

The conductivity of the tube depends upon the negative bias of the grid being sufficiently small or, in other words, upon the potential of the grid being sufficiently high with respect to that of the cathode. As pointed out previously, the potential of the grid is determined by the phase relation of the output voltage of the second of the two cascaded phase shifting bridges. The phase of the output of this second bridge depends upon the conductivity of the flame.

In order to enable a clearer understanding of these two phase shifting bridges, their relation to each other and the effect of a change in flame resistance, a vector diagram has been prepared in Figure 4 wherein there is shown the relationship between the various voltages across the different points of the phase shifting circuit. Referring to Figure 4, it will be noted that there is a long vertical vector pointed upwardly. This vector represents the voltage of the entire transformer secondary 135. Superimposed upon this long vector is a shorter vector, the extremity of which is determined by the arrow 161. This shorter vector represents the voltage between taps 164 and 161. The voltages across resistance 167 and condenser 169 are vectorially represented in Figure 4 by the vectors 172-161 and 164-172, respectively. In order to more clearly identify these two vectors with Figure 3, the resistance 167 and condenser 169 have been superimposed in dotted lines upon the corresponding vectors. The resultant output voltage of the first phase shifting bridge is designated by the vector 163-172, this voltage being the voltage which is impressed across the right-hand primary half of the autotransformer winding 176. This voltage 163-172, by reason of the fact that the resistance 167 and condenser 169 are chosen to have equal impedances, is displaced 90 degrees in phase from the voltage 164-160 of the secondary 135. Due to the autotransformer effect, there will be induced in the left-hand side of winding 176 a voltage represented by the vector 177-163. There is thus produced across the autotransformer a voltage 177-172 which is 90 degrees displaced with respect to the voltage 164-161.

The voltages across the flame and across condenser 182 are designated by the vectors 177-184 and 184-172, respectively. Again, the condenser 182 has been indicated in dotted lines to aid in the identification of the vector. Similarly, on the vector 177-184, the flame resistance has been indicated in dotted lines as a variable resistor.

The vector diagram is shown with the vectors in the position assumed when a substantial normal flame exists. Under these conditions, the voltage between junctions 163 and 184, represented by the vector 163-184, is nearly 90 degrees displaced from the voltage 177-172 so that it is almost in phase with the original supply voltage 164-161. At least it is sufficiently close to being in phase therewith that a substantial component thereof is in phase with the supply or plate voltage. This component being in phase and having the positive end thereof connected to the grid 126 results in the voltage 163-184 opposing the voltage 163-162 tending to drive the grid negatively with respect to the cathode. The biasing voltage is designated in the vector diagram by the vector 163-162. The vector

162-184 represents the resultant voltage applied to the grid and the vector 162-184' the component thereof in phase with the plate voltage. The result is that when a normal flame exists so that the vector diagram of Figure 4 is applicable, the grid biasing effect of the voltage 163-162 is sufficiently overcome to permit the tube to pass current as soon as the cathode becomes heated. Upon this happening, a circuit is established through relay 111 as follows: from the positive terminal of secondary 160 through conductor 198, relay coil 111, conductors 199 and 200, anode 127, cathode 124, and conductor 185 to tap 162.

The energization of relay coil 111 as a result of the establishment of this circuit will cause switch blade 112 to be moved out of engagement with contact 114 and switch blade 113 into engagement with contact 115. The movement of switch blade 112 out of engagement with contact 114 terminates the energization of the thermal safety switch heater 147. The movement of switch blade 113 into engagement with contact 115 results in the burner, valve, or other similar device being energized to cause fuel to flow to the burner.

The condition has been described in which the burner 150 is ignited. If the burner is not ignited, the impedance of the flame gap is extremely high. The result is that a very large portion of the voltage across the autotransformer exists across this gap. The effect of this is to rotate the voltage vector 163-184 in a clockwise direction until this vector is nearly in phase with the voltage 177-172 or 90 degrees displaced from vector 164-161. Under these conditions, the voltage 163-184, being 90 degrees displaced from the biasing voltage 163-162 and from the plate voltage 163-160, is ineffective to overcome this biasing voltage. The result is that the grid is biased negatively sufficiently to prevent any appreciable current flow to relay 111.

If on the other hand, a short circuit condition exists between the electrode and the burner 150, only a small portion of the voltage across the autotransformer exists across the flame gap, the majority of this voltage being across the condenser. The result is that the voltage vector 163-184 is rotated in a counter-clockwise direction from the position occupied in Figure 4 until this voltage vector is nearly 180 degrees displaced in phase from the voltage vector 177-172 or 90 degrees displaced from the supply voltage 164-161. The result is that again the voltage 184-163 is unable to counteract the effect of the biasing voltage 163-162. The result is that the grid is again biased negatively to a point where insufficient current flows through relay coil 111 to operate the same.

It will be noted from the preceding description that the relay is not operated if the flame resistance is either abnormally high or abnormally low. In this way, it is assured that there will be no danger of a false indication of flame by reason of a short circuit condition. This is accomplished, moreover, without the use of any triode depending upon a decrease in output current upon the establishment of flame. Thus if, with the system of the present invention, the triode should fail, the relay will go to its deenergized position. In this connection, it is to be understood that the expression "relay" or "relay means," as used in this description and in the appended claims, is intended to be broad enough to include other electronic devices which in themselves operate as relays.

It will be noted that the present species also includes a pair of concentric shields surrounding the conductor 153 between the grid and the flame electrode 152. As in the other species, the outer shield 155 is grounded at 202. The inner shield 154 is connected by conductors 203 and 180 to the junction 172. If for any reason the impedance between the inner shield 154 and conductor 153 should become sufficiently low as to interfere with the proper operation of the system, the system will be made incapable of energizing the relay, as in the previous species. It will be noted that as this impedance between the conductor 153 and shield 154 becomes reduced sufficiently, the grid 126 tends to assume the potential of junction 172, so that the second phase shifting bridge has no effect upon the voltage between grid 126 and tap 163. The result is that a voltage between grid 126 and cathode 124 consists of two components, one the phase voltage 163-162 and the voltage 163-172 which is 90 degrees displaced from the supply voltage. The voltage 163-162 which biases the grid below the cut-off point is thus unopposed with the result that the relay 111 is not energized.

Thus with this species as with the previous one, it is assured that the benefits of a shielded electrode lead are obtained without any danger of false indication of flame by reason of excessive leakage or capacitive effect between the electrode lead and its shield.

While I have described certain specific embodiments of my invention for purposes of illustration it is to be understood that I am to be limited only by the scope of the appended claims.

I claim as my invention:

1. In a flame detaching system, a burner, relay means, a grid controlled space discharge device comprising an anode, a cathode, and a control grid, means for operatively connecting said device to said relay means so that said relay means is operated only when the current flow between said anode and cathode is above a predetermined value, a periodically varying source of voltage, a control grid circuit comprising in part a connection between said grid and said source of voltage through a conductor leading from said grid and connected to an electrode extending into the burner flame, the burner being connected to said source of voltage through ground at a potential sufficiently high that when said grid is connected thereto the anode current is above said predetermined value, a shield surrounding the greater portion of said conductor and also connected to ground, and an intermediate shield coextensive with said first mentioned shield between said conductor and said first mentioned shield, said intermediate shield being connected to said source of voltage at a point that is sufficiently negative with respect to the point at which the cathode is connected that in the event of excessive capacitive effect or leakage through the insulation surrounding said conductor said grid will be subjected to a voltage such that the current flow between said anode and cathode is insufficient to operate said relay means.

2. In a flame detecting system, a burner, said burner being electrically connected to ground, relay means, a space discharge device comprising an anode, a cathode, and a control grid, a periodically varying source of voltage, connections between said source of voltage, said anode, said cathode, and said relay means to form an output circuit for said device, a connection between a portion of said circuit and ground, said

connection being so located that when said space discharge device is passing current the point of highest potential is at ground potential, a connection between said grid and ground including a conductor extending between said grid and an electrode separated from said grounded burner by a gap adapted to be bridged by the burner flame, a shield surrounding the greater portion of said conductor and connected to ground, and means for preventing a false indication of the presence of a burner flame by reason of excessive capacitance or leakage at any point through the insulation surrounding said conductor.

3. In a flame detecting system, relay means, a burner, said burner being electrically connected to ground, a space discharge device comprising an anode, a cathode, and a control grid, a periodically varying source of voltage, connections between said source of voltage, said anode, said cathode, and said relay means to form an output circuit for said device, a connection between a portion of said circuit and ground, said connection being so located that when said space discharge device is passing current the point of highest potential is at ground potential, a connection between said grid and ground including a conductor extending between said grid and an electrode separated from said grounded burner by a gap adapted to be bridged by the burner flame, a shield surrounding the greater portion of said conductor and connected to ground, and an intermediate shield between said conductor and said shield and coextensive with said first named shield, said intermediate shield being connected to said source of voltage at a point such that in the event of excessive capacitive effect or leakage through the insulation surrounding said conductor, said grid will be subjected to a voltage sufficiently negative with respect to the cathode that the current flow between said anode and cathode is insufficient to operate said relay means.

4. In a burner control system, a main burner, a pilot burner for igniting said main burner, a space discharge device comprising an anode, a cathode, and a control grid, current responsive means for causing a flow of fuel to said main burner when the current flow between said anode and cathode is above a predetermined value, a source of voltage, connections between said anode, said cathode, and said source of voltage including said current responsive means, a first connection between said grid and said source of voltage at a point operatively negative with respect to the cathode, a second connection between said grid and said source of voltage comprising a conductor leading from said grid to an electrode extending into the pilot burner flame and connections through ground between said pilot burner and said source of power at a point operatively positive with respect to the cathode, a grounded shield surrounding the greater portion of said conductor, and means for preventing a false indication of the presence of a pilot burner flame by reason of excessive capacitance or leakage at any point between the conductor and the shield.

5. In a flame detecting system, a burner, relay means, a space discharge device comprising an anode, a cathode, and a control grid, means operatively connecting said device to said relay means so that said relay means is operated only when the current flow between said anode and cathode is above a predetermined value, a source of voltage, connections between said anode, said

- cathode, and said source of voltage including said relay means, a first connection between said grid and said source of voltage at a point operatively negative with respect to the cathode, a second connection between said grid and said source of voltage comprising a conductor leading from said grid to an electrode extending into the burner flame and connections through ground between said burner and said source of power at a point operatively positive with respect to the cathode, a grounded shield surrounding the greater portion of said conductor, and means for preventing a false indication of the presence of a burner flame by reason of excessive capacitance or leakage between the conductor and the shield, said last named means comprising an intermediate shield coextensive with said first named shield and connected to said source of power at a point operatively negative with respect to the cathode.
6. In a flame detecting system, relay means, a burner, a space discharge device comprising an anode, a cathode, and a control grid, means operatively connecting said device to said relay means so that said relay means is operated only when the current flow between said anode and cathode is above a predetermined value, a source of periodically varying voltage, connections between said anode, said cathode, and said source of voltage including said relay means, a first connection between said grid and said source of voltage at a point operatively negative with respect to the cathode, a second connection between said grid and said source of voltage comprising a conductor leading from said grid to an electrode extending into the pilot burner flame and connections through ground between said pilot burner and said source of power at a point operatively positive with respect to the cathode, a grounded shield surrounding the greater portion of said conductor, and means for preventing a false indication of the presence of a burner flame by reason of excessive capacitance or leakage at any point between the conductor and the shield.
7. In a flame detecting system, relay means, a burner, a space discharge device comprising an anode, a cathode, and a control grid, means operatively connecting said device to said relay means so that said relay means is operated only when the current flow between said anode and cathode is above a predetermined value, a source of periodically varying voltage, connections between said anode, said cathode, and said source of voltage including said relay means, a first connection between said grid and said source of voltage at a point operatively negative with respect to the cathode, a second connection between said grid and said source of voltage comprising a conductor leading from said grid to an electrode extending into the burner flame and connections through ground between said burner and said source of power at a point operatively positive with respect to the cathode, a grounded shield surrounding the greater portion of said conductor, and means for preventing a false indication of the presence of a burner flame by reason of excessive capacitance or leakage at any point between the conductor and the shield.
8. In a flame detecting system, relay means, a burner, a space discharge device comprising an

anode, a cathode, and a control grid, means operatively connecting said device to said relay means so that said relay means is operated only when the current flow between said anode and cathode is above a predetermined value, an electrode extending into the path of the burner flame, and means including a phase shifting bridge comprising a connection between said grid and said electrode operative when said flame is burning to apply to said grid a potential sufficiently close to that of said cathode that sufficient current flows between said anode and cathode to operate said relay means and operative when said flame is extinguished or when the resistance between said electrode and burner is relatively low, to apply to said grid a potential sufficiently negative with respect to said cathode that the relay means is not operated.

9. In a flame detecting system, relay means, a burner, a space discharge device comprising an anode, a cathode, and a control grid, means operatively connecting said device to said relay means so that said relay means is energized only when the current flow between said anode and cathode is above a predetermined value, an electrode extending into the path of the burner flame, a conductor between said grid and said electrode, a shield surrounding the greater part of said conductor, and means operative when said flame is burning to apply to said grid a potential sufficiently close to that of said cathode that sufficient current flows between said anode and cathode to operate said relay means and operative when said flame is extinguished, when the resistance between said electrode and burner is relatively low, or when the impedance between the shield and its enclosed conductor is excessively low, to apply to said grid a potential sufficiently negative with respect to said cathode that the relay means is not operated.

10. In a flame detecting system, relay means, a burner, a space discharge device comprising an anode, a cathode, and a control grid, means operatively connecting said device to said relay means so that said relay means is operated only when the current flow between said anode and cathode is above a predetermined value, an electrode extending into the path of the burner flame, a phase shifting bridge including a center tapped source of power, and a reactance connected directly to one end of said source of power and through the flame to the other end of said source of power, and means for applying between said grid and cathode a voltage determined by the potential difference existing between the center tap of said source of power and the junction of said reactance with said flame, said phase shifting bridge being such that when the flame resistance is normal, the biasing voltage applied to the grid is sufficiently small that the relay means is operated and that when the flame resistance is either abnormally high or abnormally low, the biasing voltage is sufficiently high that the relay means is not operated.

11. In a burner control system, a main burner, a pilot burner for igniting said main burner, a grid controlled space discharge device, means for causing a flow of fuel to the burner when the output current of said device is above a predetermined value, a periodically varying source of voltage, means for connecting said voltage source in the output circuit of said device, a phase shifting bridge including a portion of said source of voltage, a reactance, and a conductive path in-

- cluding a gap normally bridged by the pilot burner flame, and means for applying the output voltage of said bridge to the grid whereby the effective grid voltage varies in accordance with the phase of said bridge output voltage, the constants of said bridge and the connections between said grid and said bridge being such that the voltage between the grid and cathode of said device is sufficiently small to result in a flow of fuel to the burner.
12. In a burner control system, a main burner, a pilot burner for igniting said main burner, a grid controlled space discharge device, means for causing a flow of fuel to the burner when the output current of said device is above a predetermined value, a periodically varying source of voltage, means for connecting said voltage source in the output current of said device, a phase shifting bridge including a portion of said source of voltage, a reactance, and a conductive path including a gap normally bridged by the pilot burner flame, means for applying the output voltage of said bridge to the grid whereby the effective grid voltage varies in accordance with the phase of said bridge output voltage, the constants of said bridge and the connections between said grid and said bridge being such that the voltage between the grid and cathode of said device is sufficiently small to result in a flow of fuel to the burner when the flame resistance is normal but sufficiently large when the flame resistance is either abnormally high or abnormally low to prevent such flow of fuel to the burner.
13. In a flame detecting system, relay means, a burner, a space discharge device comprising an anode, a cathode, and a control grid, a periodically varying source of voltage, means for connecting said voltage source in an output circuit including said relay means, said anode, and said cathode, a phase shifting bridge including a portion of said source of voltage, a reactance, and a conductive path including a gap normally bridged by the burner flame, and a grid circuit including in series a portion of said source of voltage and the output voltage of said phase shifting bridge whereby the grid is biased negatively by an amount depending upon the phase relation of the output voltage of said bridge, the constants of said bridge being such that the grid bias is sufficiently small to cause operation of the relay means when the flame resistance is normal but sufficiently large when the flame resistance is either abnormally high or abnormally low as to prevent operation of the relay means.
14. A flame detecting system for a fuel burner, comprising relay means and a circuit for operating said relay means in accordance with the impedance of the burner flame, said circuit, including in combination, a space discharge device having an input circuit and an output circuit, a source of alternating electrical energy, a connection between said output circuit and said relay means including said source of energy, a first connection between said input circuit and said source and effective to prevent the flow of current in said output circuit, and a phase-shifting bridge forming a second connection between said input circuit and said source and including said flame impedance, said phase-shifting bridge being effective when said impedance lies within a predetermined range of values to oppose said first connection and permit a flow of current in said output circuit.
